UNITED STATES PATENT OFFICE.

THOMAS SIDNEY REED, OF SYRACUSE, NEW YORK, ASSIGNOR OF ONE-HALF TO
DANIEL DENISON, OF SYRACUSE, NEW YORK.

WARP-TENSIONING DEVICE FOR LOOMS.

Application filed November 3, 1922. Serial No. 598,782.

To all whom it may concern:

Be it known that I, THOMAS SIDNEY REED, of Syracuse, New York, in the county of Onondaga, in the State of New York, have 5 invented new and useful Improvements in Warp-Tensioning Devices for Looms, of which the following, taken in connection with the accompanying drawings, is a full, clear, and exact description.

10 This invention relates to warp-tensioning attachment for looms in which the warp threads are reeled from a rotary beam into a weaving machine for interweaving with the woof threads by any of the well known 15 weaving processes.

In a machine of this character it is customary to tension the warp by the use of a greater or less number of weights which must be changed at more or less frequent 20 intervals according to the nature of the warp or the amount of warp in the beam and results in an unreliable and wide variation of the tension as the warp is unwound from the beam by reason of the continually reducing diameter of the winding.

The main object of my invention is to provide a simple and efficient tensioning device which may be easily and quickly set to produce any suitable tension according to 30 the nature of the warp and to automatically maintain substantially the same tension as the warp is gradually unwound from the beam.

In other words, I have sought to establish 35 and to maintain the desired tension through the medium of a piston pump, preferably hydraulic, in which the piston is actuated in one direction by the rotation of the warp beam to draw a suitable fluid, as oil, from a supply tank through a more or less restricted passage into the piston chamber as the beam is rotated by the travel of the warp 40 into the weaving machine whereby the suction produced by the moving piston will constitute the tensioning load upon the beam.

Another specific object is to provide 45 means, such as a valve, actuated by the rotation of the beam for gradually and automatically increasing the capacity of the fluid inlet passage to the piston chamber and thereby to gradually reduce the tensioning load in proportion as the warp is unwound so that the tension of the warp will remain substantially the same during its entire run 55 out from the beam.

Other objects and uses relating to specific parts of the tensioning device will be brought out in the following description.

In the drawings:

Figure 1 is a side elevation, partly in section, of my warp tensioning device, showing the rear end of a weaving machine including the warp beam to which the tensioning device is attached.

Figure 2 is a rear elevation of the machine, partly broken away, showing two of the warp tensioning devices, one at each end of the beam.

In order that my invention may be clearly understood, I have shown a warp-beam 70 —A— as journaled at its ends in suitable bearings on the opposite sides of the rear end of a weaving machine frame —B— for receiving and supporting the warp as —C— which when drawn into the machine in the 75 usual manner causes the rotation of the beam in the direction indicated by arrow —e— Figure 1.

I preferably employ two tensioning devices, one at each side of the machine, to secure a more perfect balance of tension of the threads throughout the length of the beam and also to permit them to act alternately if it should be found necessary by simply adjusting the disks on the ends of 85 the beam so as to bring the piston-actuating pins of each out of alignment with those of the other beam, but the operation of each device is substantially the same and therefore, the description of one will apply to 90 both.

Secured to each of the opposite-ends of the beam —A— is a circular disk —1— to rotate therewith and each disk is provided with a series of, in this instance seven pins 95 —2— projecting axially from the outer faces thereof.

Associated with each disk is an upright piston pump —3— having a cylinder —4— and a piston —5— movable therein and provided with a rod —6— extending through a gland —7— in the top of the cylinder which is provided with the usual vent (not shown) in its upper end to avoid trapping of the air therein.

The lower end of the cylinder —4— is secured in the upper side of a liquid reservoir or supply tank —8— which contains a sufficient supply of liquid, as oil, to more than fill the cylinder when the piston is at 110

its upward limit of movement and is preferably provided with openings —9— in its upper side to avoid vacuum and allow the fluid to rise and fall in the cylinder with 5 the movements of the piston.

A tubular extension —10— is screwed in the lower end of the cylinder —4— with its lower end always below the level of the liquid in the supply tank —8— and, in 10 the upper end of this extension is screwed a partition —11— having a restricted passage —12— connecting the interior of the reservoir —8— with the interior of the cylinder below the limit of downward movement of the piston to allow the fluid to pass more or less slowly from one chamber to the other as the piston is raised and lowered.

Each piston rod —6— is provided with 20 a pivoted pawl or dog —13— having its free upper end spring pressed into engagement with the pins —2— as the latter are successively presented thereto by the rotation of the beam, said pawl being provided 25 with a recess or notch —14— for receiving the registering pin whereby the piston will be drawn upwardly by the continued rotation of the beam until the pawl is tripped by the next succeeding pin.

The partial vacuum or suction produced 30 by this upward movement of the piston draws the liquid from the reservoir —8— into the cylinder —4— through the restricted passage —12— and therefore introduces a certain amount of resistance or 35 load upon the beam and a resultant corresponding tensioning of the warp depending upon the relative size of the restricted passage —12— as controlled by a needle valve 40 —15—. That is, in setting the machine, the smaller the passage, the greater will be the resistance to the upward movement of the piston, and consequently greater tensioning of the warp, while the enlarging of 45 the passage reduces that resistance, and tension, the function of the valve —15— being to control the size of the passage and thereby to control the tension of the warp.

The pins —2— are preferably arranged 50 in a circle of approximately the diameter of the roll of warp on the beam as for example, when starting the machine so that the ratio of leverage between the power as the pull of the warp upon the beam to the 55 load of lifting the piston through the medium of the disk —1— and pins —2— is substantially one to one, but owing to the fact that the leverage acting upon the load is constant, while that of the power 60 gradually reduces by the gradual unwinding of the warp from the beam, it becomes necessary to gradually reduce the load or resistance to the upward movement of the piston as the warp is unwound by gradually 65 opening the valve —15— producing a cor-

responding enlargement of the passage —12—.

This adjustment of the valve is preferably controlled automatically and for this purpose the stem as —16— of the valve is 70 extended downwardly through a gland —17— in the bottom of the reservoir —8— and is provided with screw threads —18— adapted to be engaged by a nut —19— which is held against axial movement by a bracket —20— having guide openings 75 therein for additionally supporting the stem of the valve against lateral movement.

The nut —19— is provided with a peripheral worm gear —21— meshing with a worm —22— on the shaft —23— which is journaled in suitable bearings on the adjacent side of the frame —B— and is provided with a ratchet wheel —24—.

A ratchet operating pawl —25— is 80 slideable vertically in suitable ways —26— on the frame —B— and has its lower end provided with a hinged toothed section —27— spring pressed into engagement with the teeth of the ratchet wheel by a spring —28— to enable the member —27— to ride over the tooth of the ratchet wheel when the pawl descends after having been raised to operate the ratchet wheel one tooth space at a time and thereby, to effect a corresponding adjustment of the valve —15— through the medium of the worm —22—, gear —21—, and nut —19—.

The upper end of the pawl —25— is provided with a tooth —29— adapted to be engaged by a cooperative tooth —30— on the periphery of the adjacent disk —1— whereby the pawl will be raised to operate the ratchet wheel —24— one tooth space at each revolution of the beam —A— or as 105 each layer of warping is gradually unwound therefrom, it being understood that following each operation of the pawl, the pin —30— rides out from under the tooth —29— to release said pawl and allow it to return by its own weight for re-engagement with the next succeeding tooth of the ratchet wheel —24— ready to repeat the operation of adjusting the valve during the next 110 revolution of the beam, and so on until the warp is entirely unwound from the beam during which the valve —15— will be gradually opened more and more to reduce the 115 resistance to the rotation of the beam as the warping unwinds therefrom.

The lower end of the valve stem below the bracket —20— is provided with a hand wheel —31— having a notched periphery adapted to be engaged by a spring catch —32— to permit the valve to be reset or 125 adjusted at will, the catch —32— serving to hold the valve against undue rotation during its automatic adjustment through the medium of the nut —19— and its actuating means.

A coil spring —33— is interposed between the piston —5— and upper end of the cylinder —4— to assist the piston in its downward movement when released by the disengagement of the pawl —13— but it is evident that the tension of this spring may be utilized with the partial vacuum produced by the upward movement of the piston in exerting additional tension upon the warp.

When the machine is ready for operation with the full warp beam, the valve —15— is adjusted or set by hand to a position which will produce the maximum tension required or nearest to its closed position with the piston —5— and parts carried thereby in their extreme down positions, and as the warp is drawn into the machine the beam and disks —1— will be rotated in a direction indicated by arrow *a*, Figure 1, thereby bringing one of the pins nearest to the pawl —13— in engagement with the notch —14— to gradually raise the piston and thereby to draw the liquid from the reservoir —8— into the cylinder below the piston by reason of the partial vacuum or suction produced by the raising of the piston.

The spacing of the pins —2— and their relation to the pawl —13— is such that when the piston is elevated a pre-determined distance or too near the upper end of the cylinder, by one of the pins, the next succeeding pin will trip the pawl and thereby release the piston, but owing to the slowness with which the liquid can escape from the cylinder through the restricted passage —12— the piston will be prevented from sudden descent and will remain more or less elevated until the notch —14— in the pawl is engaged by the next succeeding pin which will again raise the piston to its extreme up position.

The short intervening period between the disengagement of the pawl by one pin and its reengagement by the next pin temporarily releases the tension, at a time when such release is desired, as for example, when opening the warping to permit the shuttle to pass therethrough.

As each succeeding layer of warp is unwound from the beam, the pin —30— will engage the shoulder —29— and lift the pawl —25— to operate the ratchet wheel 24 one tooth space and thereby to adjust the nut —19— rotarily a small fraction of a turn to effect a further slight opening of the valve and thereby to increase the size of the passage —12— to reduce the resistance to the elevation of the piston, and to maintain a substantially uniform tension

on the warp as the latter is unwound from the beam.

The disks —1— are adjustable rotarily upon the ends of the beam —A— so that if desired to obtain a practically continuous tension on the warp, the pawls —13— and corresponding posts may be lifted alternately by the engagement of the pawl —13— at one end with one of the pins of the adjacent disk —1— at about the same time that the opposite pawl has been released after it has drawn its piston to the limit of its upward movement.

While I have shown a pair of hydraulic pumps and suitable connections with both ends of the warp beam, I do not wish to limit myself to the number of pumps nor to the particular means for transmitting motion from the beam to the pump pistons, nor to the means for transmitting motion from the warp beam to the valve —15—.

I claim:

1. In a warp tensioning device for looms, the combination with a rotary warp-actuated beam, a piston chamber, a fluid supply reservoir connected by a restricted passage with the piston chamber, a piston movable in said chamber, means actuated by the rotation of the warp beam for moving the piston in one direction to draw the fluid from the reservoir into the piston chamber through the restricted passage, and means for varying the size of said passage to vary the suction resistance to the operation of the piston by the warp beam and thereby to vary the tension of the warp.

2. In a warp tensioning device for looms, the combination with a rotary warp-actuated beam, a piston chamber, a fluid supply reservoir connected by a restricted passage with the piston chamber, a piston movable in said chamber, means actuated by the rotation of the warp beam for moving the piston in one direction to draw the fluid from the reservoir into the piston chamber through the restricted passage, a valve for varying the size of said passage to vary the suction resistance to the operation of the piston by the warp beam and thereby to vary the tension of the warp, and means actuated by the rotation of the warp beam for gradually opening the valve to reduce said suction resistance as the warp is unwound from the beam.

In witness whereof I have hereunto set my hand this 18th day of October 1922.

THOMAS SIDNEY REED.
